SHOE FINISHING APPARATUS

Harry H. Parks, Huntington Park, Lee A. Thomas, Maywood, and Howard S. Thomas, Huntington Park, Calif.

Application September 11, 1935, Serial No. 40,070

1 Claim. (Cl. 51—109)

This invention relates to shoe finishing machines.

The general object of our invention is to provide an improved shoe finishing machine by means of which the sole or other part of the shoe may be properly finished and wherein novel means is provided for removing the material taken from the shoe.

Another object of the invention is to provide an improved shoe finishing machine including an abrasive wheel with a novel suction member for removing the material taken from the shoe.

A further object of our invention is to provide an improved mounting for the abrasive member of a shoe finishing machine.

Other objects and the advantages of our invention will be apparent from the following description taken in connection with the following drawing wherein:

20 Fig. 1 is a side elevation of a machine embodying the parts of our invention;

Fig. 2 is a side elevation partly in section showing the machine;

Fig. 3 is a top plan view of the machine; and

25 Fig. 4 is a bottom plan view of the machine.

Referring to the drawing by reference characters we have shown our invention as embodied in a shoe finishing machine which is indicated generally at 10.

30 As shown the machine 10 is mounted on a base 11 which may be made of wood and which is provided with a slot 12. On the base 11 we show a pair of brackets 13. Each bracket is L-shaped and includes a portion 14 which is secured by bolts 15 to the base 11. Each bracket further includes an upstanding portion 16 which has slots 17 therein through which bolts 18 pass. These bolts 18 engage a motor pedestal 19 to hold this pedestal in position. By means of the slots 17

35 the vertical position of the pedestal 19 can be adjusted. The pedestal 19 supports a motor housing 20 within which is an electric motor which has an armature shaft 21 projecting from one end and an armature shaft 22 projecting from the other end. The lower end of the armature shaft 21 is threaded as at 23 and over this threaded portion we arrange a removable sleeve 24.

40 On the threaded end 23 we threadedly secure an abrasive wheel support 25 and on this support 25 we arrange a sponge rubber disc 26. An abrasive member 27, such as sand paper is secured to the disc 26. The armature shaft end 22 has a fan rotor 28 suitably mounted thereon and above this fan rotor 28. We provide a casing 29 which is shown as connected by screws

30 to the motor housing 20. The casing 29 is provided with an air inlet 31 which communicates with a conduit 32. This conduit 32 is U-shaped and is secured to the casing by screws 33. The conduit 32 passes through the slot 12 and terminates in a segmental housing 34 which is disposed adjacent the abrasive member 27. This housing 34 has a top wall 35, a bottom wall 36, and an outer peripheral wall 37. The inner face 38 of the housing 34 is open. One end of the 10 housing 34 is closed by the closure plate 39 which may be held in place by the screws 40, but the other end of the housing 41 is open.

In operation the machine is mounted on a base, as described, and when the motor is operating 15 the rotor 28 produces a suction, creating a partial vacuum in the conduit 32 and a partial vacuum in the segmental housing 34. This partial vacuum draws the material removed from the shoe into the conduit 32 and also draws any material such as dirt or abraded material from the abrasive member 27 through the conduit 32, whence it passes into the housing 29 and out through an exit 42 in the housing to a conduit 43 where it may pass to a suitable receiver for 20 the waste material. The slots 17 allow the machine to be adjusted vertically relative to the base 11, while by removing the sleeve 24 and placing a longer or shorter sleeve thereon the position of the abrasive member 27 relative to the 30 bottom 36 of the housing 34 can be adjusted.

Preferably the abrasive member 27 is disposed just below the plane of the bottom wall 36, also the exact position will depend upon the requirements of the work being performed. It will be 35 understood, of course, that the rotor 28 and casing 29 can be mounted below the motor on the shaft 21, which may be elongated for this purpose, and just above the abrasive support 25 instead of as shown, and that in this construction 40 the length of the U-shaped conduit 32 would be much inclined.

From the foregoing description it will be apparent that we have invented a novel shoe finishing machine which is simple in construction 45 and highly efficient in use.

Having thus described our invention we claim:

In a shoe finishing machine, a support having a pair of brackets mounted thereon, a motor including a pedestal and an armature shaft, 50 means to adjustably mount said pedestal on said brackets with the armature shaft vertical, a housing for said motor, said armature shaft projecting beyond each end of the motor housing, an abrasive wheel on one end of said shaft, the 55

other end of said shaft having a fan rotor mounted thereon, a casing surrounding said rotor, said casing being secured to said motor housing, said casing having an inlet, a conduit 5 opening into said inlet, said conduit being U-shaped and extending around said fan casing and said motor housing and between said brackets and including an inlet portion disposed adjacent said abrasive wheel, said inlet portion including 10 a segmental housing horizontally disposed and extending for more than 180° about the abrasive

wheel, said housing having an outer peripheral wall and upper and lower walls and having an opening to the interior, said opening being disposed adjacent said abrasive member, a closure for one end of said opening, the other end of 5 said opening being open, said fan rotor casing having an exit therefrom and a flexible member communicating with said exit.
